UNITED STATES PATENT OFFICE

148,183

DESIGN FOR A COMBINED BRACELET AND COSMETIC CONTAINERS

Sidney Packales, New York, N. Y.

Application June 13, 1947, Serial No. 139,664

Term of patent 3½ years

(Cl. D45—4)

To all whom it may concern:

Be it known that I, Sidney Packales, a citizen of the United States of America, residing in New York, county of New York, and State of New York, have invented a new, original, and ornamental Design for a Combined Bracelet and Cosmetic Containers, of which the following is a specification, reference being had to the accompanying drawing, forming part thereof.

Fig. 1 is a front perspective view of a combined bracelet and cosmetic containers showing my new design.

Fig. 2 is a fragmentary view illustrating one of the cosmetic containers in open position.

The opposite side of the combined bracelet and cosmetic containers shown in Fig. 1 is substantially plain.

I claim:

The ornamental design for a combined bracelet and cosmetic containers, substantially as shown and described.

SIDNEY PACKALES.
